APPARATUS FOR DETERMINING AND RECORDING THE DUST CONTENT OF FLUE GAS

Worrell Hansell Holby, New Rochelle, N. Y., assignor to The General Power Plant Corporation, Ossining, N. Y., a corporation of New York

Application December 18, 1951, Serial No. 262,296

2 Claims. (Cl. 250—218)

1

This invention relates to apparatus for determining and recording the dust content of flue gas.

Manufacturing plants, such as steel mills, have large quantities of gas coming from the blast furnaces, which have considerable fuel value. However, this gas contains a great deal of very abrasive dust and grit which is carried over from the coke and iron ore and which causes clogging and wear in pipes, valves, etc.

To make this gas available it is put through a scrubber and then through an electrostatic precipitator. This cleans the gas and removes most of the dust and the cleaned gas is saturated with water.

This invention was developed for the purpose of continuously monitoring and recording the gas in order to keep track of the dust content. This problem is rendered difficult because of the amount of water vapor in the gas and because the gas is under positive pressure and is poisonous.

This invention has for its salient object to provide simple and practical apparatus for continuously and accurately analyzing and recording the dust content of flue gas.

Another object of the invention is to provide apparatus of the character described, involving the use of a photo-electric cell and energizing lamp and so constructed and arranged that the lenses will remain clean and clear.

Another object of the invention is to provide apparatus of the character described, involving the use of a photo-electric cell and energizing lamp and so constructed and arranged that the lenses will remain clean and clear but the gas sample will not be diluted.

Another object of the invention is to provide apparatus of the character described, so constructed and arranged that the analyzer and recorder can be easily and quickly zeroed and calibrated.

Another object of the invention is to provide apparatus so constructed and arranged that the length of the gas sample being analyzed can be regulated so that the length can be reduced for very dense or dirty gas.

Further objects of the invention will appear from the following specification taken in connection with the drawings which form a part of this application, and in which

Fig. 1 is a longitudinal sectional elevation illustrating apparatus embodying the invention;

Fig. 2 is a diagrammatic elevational view showing the circuits for the apparatus and illustrating diagrammatically the operative parts thereof;

Fig. 3 is an end elevation taken substantially at right angles to Fig. 1; and

Fig. 4 is a sectional elevation showing means

2

for adjusting the energizing lamp relative to the lens.

In the particular embodiment of the invention illustrated in the drawings there is shown a sampling tube or cylinder 10 having heads 12 and 13 at the ends thereof. The gas to be sampled is conducted from a gas main 15 through a conduit 16 to a conduit 17 and thence through a conduit 18 to the approximate longitudinal center of the tube 10. The inlet opening from the conduit 18 into the tube is shown at 19. Outlet ports 20 and 21 are provided at the end portions of the sampling tube 10 and the gas escaping through the outlet ports is burned by a gas flame 22 from a gas cock 23.

A drain pipe 25 is connected to the conduit 17 and connects at its bottom with a pipe 26 which also communicates a drain pipe 27 which, at its other end, communicates with the sampling tube 10.

The conduit 17 on opposite sides of the center thereof has connected thereto manometers 30 and 31 and also valves 32 and 33. At the right of the center, viewing Fig. 1, there is connected to the conduit 17 a thimble 34 and a meter 35 which are used in the usual manner to measure and weight measured quantities of gas.

The head 12 of the tube or cylinder 10 has mounted therein a tube 40, which has mounted in the outer end thereof an energizing lamp 41 and a reference cell 42 which is adapted to receive the light rays directly from the lamp. However, in order to vary the amount of light reaching the reference cell from the energizing lamp, adjustable Polaroid filters 43 and 44 are interposed between the lamp and the reference cell.

Within the tube 40 is adjustably mounted a telescoping tube 45 having a lug 46 at the inner end thereof which is threaded and is mounted on a rotatable screw 47 which is carried by the heads 12 and 13 and extends throughout the length of the tube 10. The outer end of the screw 47 has mounted thereon a head 48 by means of which it can be rotated.

The head 13 has mounted therein a tube 50 on the outer end of which is mounted an analyzing photo-electric cell 51. Within the tube 50 is slidably mounted a telescoping tube 52 having a lug 53 provided with a threaded opening and mounted on the screw 47. The threads at one end of the screw 47 will be left hand threads and those at the other end will be right hand threads, so that when the screw is rotated the telescoping tubes 45 and 52 will be moved simultaneously toward and away from each other.

The purpose of providing the adjustable telescoping tubes is to vary the length of the gas column to be analyzed. For instance, when the

gas is very dense or heavy with dust, the tubes 45 and 52 are moved toward each other so that the rays between the lamp and the energizing cell will pass through a shorter length of gas column. When the dust content is less the length of the gas column analyzed will be greater and to accomplish this the telescoping tubes 45 and 52 will be moved away from each other.

One of the objects of the invention is to prevent dust and moisture from obscuring the lenses in the lamp tube and analyzing cell tube and this is accomplished in the following manner. A pipe 55 is connected to a source of compressed air supply and communicates through a pipe 56 with a pipe 57. The ends of the pipe 57 are connected by pipes 58 and 59 to the tubes 49 and 50 adjacent the outer ends thereof, thereby introducing clean air into the tubes 49 and 50 and also into the telescoping tubes 45 and 52. This air will keep the tubes 40, 45 and 50, 52 clean and free from dust and moisture. The air will pass inwardly through the tubes and will pass from the tube 40 through the outlets 20 and 21 to the atmosphere. Thus, the lamp tube and analyzing tube will be kept clean and, furthermore, the gas sample in the tube 40 will not be diluted by the clean air.

The conduits 58 and 59 in the embodiment of the invention shown have mounted therein sight flow indicators 60 and 61 and valves 62 and 63.

In Figs. 1 and 2, the recorder R, which makes a record of the dust content in the gas main as determined by the analysis made in the sampling tube, is controlled and operated by the difference in output between the analyzing cell 51 and the reference cell 42. The analyzing cell receives the light from the lamp 41 through the sample of gas being analyzed in the tube 10. On the other hand, the reference cell 42 receives its light directly from the energizing lamp 41.

The circuit utilized in the apparatus is illustrated diagrammatically in Fig. 2. In this circuit the positive terminal of the analyzing cell 51 is connected to the negative terminal of the reference cell 42 by a wire 65. The positive terminal of the reference cell 42 is connected to an adjustable contact 66 of a bridge circuit. In this circuit a variable resistance wire 67 is connected at one end by a wire 68 to the negative terminal of the analyzing cell 51. The other end of the variable resistance wire 67 is connected through a resistance 69 to the wire 65. The recorder R is connected across the wires 65 and 68.

The recorder is zeroed by adjusting the circuit so that the output of the cells 42 and 51 is equal when the sampling tube 10 is filled with clean air. This is accomplished by first adjusting the Polaroid filters 43 and 44 so that less light will reach the reference cell 42 than will reach the analyzing cell 51 when the sampling tube is filled with clean air and the lamp is at the focal point of the lens L disposed in the lamp tube 40. The two cells 42 and 51 are then brought into balance by moving the lamp 41 ahead of the focus point of the lens L, thus dispersing or scattering the light on the analyzing cell 51. This is accomplished by an adjusting screw 70 accessible at the back of the casing of the energizing lamp 41.

As hereinbefore stated, in order to analyze or measure very dirty gas, it is necessary to reduce the length of the sample in order to keep the reading on the chart. This is accomplished by sliding the telescoping sleeves or tubes 45 and 52 inwardly by the rotation of the screw 47. In this way the length of the sample can be reduced from sixty

inches to twenty inches. The sensitivity of the recorder R can be increased by adding resistance 69 to the end of the resistance 67, thus increasing the pen travel by unit of dust in the sample.

5 The recorder R must be calibrated for each type of gas and for each setting of the sampling tube, that is, each variation in length of the sample to be analyzed. The width or length of the sample will be altered in accordance with the density of
10 the dust content. The calibration of the recorder is accomplished by measuring the actual solid content of the gas, using the thimble 34 and meter 35 in the usual manner.

15 By introducing the gas to be analyzed into the longitudinal center of the sampling tube 10 and by introducing clean air in the outer ends of the tubes 40 and 50, the lenses in the lamp and analyzing cell tubes will be maintained clear and will not be affected by any moisture or dust which 20 is present in the sampling tube. Moreover, by introducing the air in the manner described, the sample being tested will not be diluted by the air used to keep the tubes 40 and 50 clear and free from moisture and dust.

25 Moreover, the circuit above described and the use of the reference cell in the manner outlined eliminates any error which might be caused by line voltage variations in the energizing lamp circuit.

30 Although one specific embodiment of the invention has been particularly shown and described it will be understood that the invention is capable of modification and that changes in the various cooperating parts may be made without departing 35 from the spirit or scope of the invention as expressed in the following claims.

What I claim is:

1. Gas analyzing apparatus comprising a sampling tube, means for introducing gas to be analyzed into the central portion of the tube, gas and air exhaust conduits at the end portions of the tube, a lamp tube extending longitudinally into one end of the sampling tube, an energizing lamp at the outer end of said lamp tube, a third tube extending into the other end of the sampling tube, a photo-electric analyzing cell at the outer end of said last named tube, and means for introducing air into said lamp tube and analyzing cell tube adjacent the lamp and cell.

50 2. Gas analyzing apparatus comprising a sampling tube, means for introducing gas to be analyzed into the central portion of the tube, gas and air exhaust conduits at the end portions of the tube, a lamp tube extending longitudinally 55 into one end of the sampling tube, an energizing lamp at the outer end of said lamp tube, a third tube extending into the other end of the sampling tube, a photo-electric analyzing cell at the outer end of said last named tube, adjusting means for 60 changing the distance between the inner ends of the tubes extending into the sampling tube, and means for introducing air into said lamp tube and analyzing cell tube adjacent the lamp and cell.
